UNITED STATES PATENT OFFICE.

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-REPLENISHING LOOM.

Application filed March 19, 1925. Serial No. 16,791.

This invention relates to a replenishing loom of the type in which a plurality of shifting shuttle boxes are provided on the magazine end of the loom which is an essential construction in pick and pick looms.

It is one object of my invention to provide a new and improved arrangement of such shuttle boxes, by which the replacement of an exhausted bobbin is facilitated.

Another object is to provide a construction by which any selected shuttle box may be brought to operative position by movement over a minimum distance.

A further feature of my invention relates to the provision of improved devices for supporting the shuttle boxes for movement in a closed path, and for guiding a discharged bobbin and preventing lodgment thereof in the moving parts of the loom.

My invention further relates to arrangements and combinations of parts which will be hereinafter described and more particularly pointed out in the appended claims.

A preferred form of the invention is shown in the drawings, in which

Fig. 1 is a side elevation of the left hand side of a loom, with the usual drop boxes shown in section;

Fig. 2 is a partial side elevation of the right hand side of the loom, with my improvements applied thereto:

Fig. 3 is an enlarged front elevation of the magazine end of the lay and parts mounted thereon:

Fig. 4 is an end elevation of the shuttle boxes and the structure supporting the same, looking in the direction of the arrow 4 in Fig. 3;

Figs. 5 and 6 are sectional end elevations, taken along the lines 5—5 and 6—6 in Fig. 3;

Fig. 7 is a plan view, looking in the direction of the arrow 7 in Figs. 3 and 4;

Fig. 8 is a sectional front elevation, taken along the line 8—8 in Fig. 4; and

Fig. 9 is a partial end elevation, looking in the direction of the arrow 9 in Fig. 3;

Referring to the drawings, I have shown my invention applied to a weft replenishing loom having three shifting shuttle boxes at each end of the lay and accordingly capable of operation as a pick and pick loom, the picking mechanism being omitted. I have shown three shuttle boxes 10 (Fig. 1) of the usual type supported for vertical movement

at the non-replenishing end of a lay 11 and 55 actuated by pattern-controlled drop-box mechanism of any usual type.

For the purposes of this application, I have indicated a lever 12 pivoted at 13 to the loom side 14 and connected by a give-way 60 connection 15 to the drop box lifter rod 16. The lever 12 is provided with links 17 and 18 connecting the lever 12 to crank pins in pinions 19 and 20. These pinions are intermittently rotated to raise or lower the crank pins by a mutilated gear 21. By selectively and partially rotating one or the other or both of the pinions 19 and 20, the lever 12 may be given a plurality of selected angular positions, thus raising and lowering the drop 70 boxes 10. The drop box mechanism thus described is old in the art and forms no part of my present invention.

I have also provided a second pair of pinions 22 and 23 connected by links 24 and 25 to a pair of lever arms 26 and 27. These arms 26 and 27 are mounted on shafts 28 and 29 supported in brackets 30 on the loom frame and extending across the loom to the magazine end thereof. Actuating arms 31 and 32 are mounted on the magazine ends of the shafts 28 and 29 respectively and control the movements of shifting shuttle boxes at the magazine end of the loom as will be hereinafter described.

I have shown three shuttle boxes 35 at the magazine side of the loom, these shuttle boxes being mounted upon a support 36 which is rotatable in bearings or brackets 37 and 38 formed on a lay end 39. This lay end is preferably secured to the lay 11, although it is within the scope of my invention to mount the lay end 39 for movement independent of the lay.

The details of construction of the support 36 and its bearings are best shown in Fig. 8, in which it will be seen that the support 36 is provided with a disc or head 40 rotatable on ball bearings 41 in the bracket 37. At its opposite end the support 36 has 100 an extension 42 having a roller bearing 43, the inner ring of which is mounted upon a stud 44 fixed in the bracket 38. A gear 45 is fastened to a flange on the end of the extension 42 and constitutes means for rotating the shuttle box support 36.

A fixed bobbin guide 46 is mounted on the stud 44 and has a bearing at its outer end

in the support 36. The guide 46 is held from rotation and is provided with a bobbin passage 47 for a purpose to be explained.

In the preferred form of my invention, 5 three shuttle boxes only are used on the rotary support 36, but certain features of my invention are of more general application and as to such features I do not wish to be limited to a specific number of boxes.

10 The running shuttle is always in the upper or horizontally positioned box 35 and is actuated by a picker 48 slideable on a fixed rod 49 actuated by the usual picker stick 50. Each shuttle box 35 is open at its upper side, as indicated at 51 in Figs. 6 and 8, to admit a fresh bobbin and is also open, as shown at 52 at the bottom of the box to permit ejection of the exhausted bobbin. Reference to Fig. 6 will show that the opening 52 in the bottom of the shuttle box is aligned with the opening 47 in the guide member 46 previously described. It also appears from Fig. 6 that the shuttle boxes 35 are spaced apart sufficiently to provide 20 openings between the boxes at least equal in width to the openings 47 and 52.

Where an odd number of shuttle boxes is used, one of the spaces between the boxes will be directly below the guide opening 47 30 when any one of the boxes 35 is in operative position. The ejected bobbin thus has a clear passage downward to the bobbin can or other receptacle for the ejected bobbins.

35 I will now describe the mechanism for rotating the support 36 to selectively position the shuttle boxes 35. For this purpose I have provided a pair of rack bars 55 mounted at the upper end of a rod 56 which is pivoted at its lower end to the actuating lever 32. I have also provided a cross slide 57 (Fig. 9) having rolls 58 engaging the outer faces of the rack bars 55.

40 The slide bar 57 is mounted in guideways 59 (Fig. 8) in the bracket 38^a and is provided with a stud 60 projecting into a cam slot 61 (Fig. 9) in a cam plate 62 mounted on the upper end of a rod 63 which is pivoted at its lower end to the actuating arm 31. The cam plate 62 is slideable in guideways 64 (Fig. 7) in the bracket 38^a (Fig. 8) and determines the transverse position of the slide bar 57 and the rolls 58.

45 As the pinion 23 (Fig. 1) is given partial rotations to raise or lower the lever 27, the rod 63 is correspondingly lowered or raised and the slide bar 57 is moved to the left or right to cause one or the other of the rack bars 55 to engage with the gear 45 on the shuttle support. Subsequent partial rotation of the pinion 22 will raise or lower the rod 56 and rack bars 55, thus rotating the shuttle support in one direction or the other, depending on which rack bar engages the gear 45.

When three shuttle boxes are used, as shown in the drawings, this selective operating mechanism presents very important advantages, as the shuttle boxes can be rotated in either direction at any time, and 70 any one of the three boxes can thus be brought into operative position by moving it the distance between the center lines of two adjacent boxes. In the usual straight line arrangement of drop boxes, as shown 75 in Fig. 1, it is frequently necessary to move the space of two or more boxes in order to change from an upper to a lower box. By this decreased movement I am also able to decrease the time required for positioning 80 the box and I thus have more time available for the transfer of the bobbin.

The magazine mechanism indicated in Fig. 2 is illustrative only and comprises a portion of a rotary multi-color magazine 85 of the type fully shown and described in the patent to Ryon, No. 966,402, patented August 2, 1910. For the purposes of this application it is sufficient to state that the rotary magazine 70 is provided with bobbins in sets of three, one for each shuttle, and that the magazine is adjusted to bring a bobbin corresponding to the running shuttle to transfer position by the rotation of a worm 71 engaging a worm wheel 72 on the 90 magazine. The worm 71 is mounted on a shaft 73 which is rotated backward and forward in accordance with the box changes and which is also given a direct endwise movement to advance the magazine to the 100 next series of bobbins, as soon as one of the bobbins in a series has been transferred. For a further description of this mechanism reference is made to the Ryon patent above cited. 105

Having described my invention and the advantages thereof, the method of operation will be apparent without further description. It will be also evident that changes and modifications can be made within the 110 spirit and scope of my invention as set forth in the claims and I do not wish to be otherwise limited to the details herein disclosed but what I claim is:—

115 1. In a weft replenishing loom, a magazine, more than two shuttle boxes mounted at the magazine end of the loom, means to support said boxes for movement in a circular path, and selective means effective to move said boxes in either direction at any time said means being thereby effective to present any selected box in operative position at any time by a rotary movement of said box through a single space only.

120 2. In a weft replenishing loom, a magazine, more than two shuttle boxes mounted at the magazine end of the loom, shuttles for said boxes having a bobbin passage from top to bottom thereof, said boxes having 125 corresponding openings in their shuttle sup-

porting surfaces, means to support said boxes for movement in a circular path, and actuating means to bring any selected box to operative position on any selected pick.

5. 3. The combination in a loom as set forth in claim 2, in which an odd number of boxes is provided, and in which said boxes are spaced apart to provide discharge openings for ejected bobbins between adjacent boxes.

10. 4. The combination in a loom as set forth in claim 2, in which the supporting means is provided with an axially extended and downwardly directed passage through which a bobbin may be ejected.

15. 5. The combination in a loom as set forth in claim 2, in which the supporting means is rotatably mounted, in which three shuttle boxes are mounted on said rotary support and in which the actuating means is selectively operated to bring any selected box to operative position by movement equal to the distance between two adjacent box centers.

6. The combination in a loom as set forth in claim 2, in which the supporting means is provided with a gear, in which the actuating means is provided with spaced rack bars, and in which selective means is provided to move said rack bars to engage a selected rack bar with said gear before actuating movement of said bars.

30. 7. In a loom, an odd number of shuttle boxes, shuttles for said boxes, a rotary support on which said boxes are mounted in spaced relation, and selective means to rotate said support to bring a selected box to operative position, said shuttles, said shuttle boxes, and said support each having openings therein forming a discharge passage for an exhausted bobbin from a running shuttle, said boxes being spaced apart to permit passage of the discharged bobbin between the two lowermost boxes.

45. 8. In a weft replenishing loom, a magazine, a lay, a plurality of shuttle boxes mounted on a rotary support at the magazine end of the lay, a gear on said support, a pair of rack bars vertically slidable one

at each side of said gear, means to definitely space said bars apart at all times so that a single rack bar only can engage with said gear at any one time, and pattern controlled means to move said bars laterally to cause a selected bar only to engage said gear.

9. In a weft replenishing loom, a magazine, a lay, a plurality of shuttle boxes mounted on a rotary support at the magazine end of the lay, a gear on said support, a pair of rack bars vertically slidable one at each side of said gear but spaced apart to permit a single rack bar only to engage with said gear at any one time, a transversely slidable member connected with said rack bars, and pattern controlled means to move said member.

10. In a weft replenishing loom, a magazine, a lay, a plurality of shuttle boxes mounted on a rotary support at the magazine end of the lay, a gear on said support, a pair of rack bars vertically slidable one at each side of said gear but spaced apart to permit a single rack bar only to engage with said gear at any one time, a transversely slidable member connected with said rack bars, and a pattern controlled vertically movable member having a pin and cam slot connection with said slidable member.

11. In a weft replenishing loom, a magazine, a lay, a plurality of shuttle boxes mounted on a rotary support at the magazine end of the lay, a gear on said support, a pair of rack bars vertically slidable one at each side of said gear, means to definitely space said bars apart at all times so that a single rack bar only can engage with said gear at any one time, pattern controlled means to shift said rack bars transversely to cause a selected rack bar only to engage said gear, and pattern controlled means to move said rack bars vertically to shift said boxes.

In testimony whereof I have hereto affixed my signature.

ALBERT A. GORDON.
